UNITED STATES PATENT OFFICE.

RICHARD HAMMILL, OF CHICAGO, ILLINOIS.

PLATFORM FOR FIRE-ESCAPES.

SPECIFICATION forming part of Letters Patent No. 316,960, dated May 5, 1885.

Application filed September 16, 1884. (No model.)

To all whom it may concern:

Be it known that I, RICHARD HAMMILL, a citizen of the United States of America, residing at Chicago, in the county of Cook and State of Illinois, have invented certain new and useful Improvements in Platforms for Fire-Escapes, of which the following is a specification, reference being had therein to the accompanying drawings.

10 My invention relates to an improved platform especially adapted to use in connection with fire-escape ladders secured to buildings.

The object of the invention is to so construct these platforms that all collection of ice, &c., will be avoided, and a sure and comfortable foothold obtained.

To the accomplishment of the above the invention consists in forming a platform of a number of cross-bars, each roughened upon 20 its upper face, and the side edges of each bar being formed on an incline, the bars being so arranged that a number of square or diamond-shaped openings will be formed in the platform.

25 Reference will be made to the accompanying drawings, in which Figure 1 is a plan view of the platform, and Fig. 2 a section of part thereof on an enlarged scale.

Like letters refer to like parts in each view. 30 The platform consists of a frame-work, *a*, and a suitable number of cross-bars, *b*. At suitable points openings *c* may be formed for the passage therethrough of suitable standards or vertical pieces which form the side 35 rails of the ladder in connection with which the platforms are to be used, and an opening, *d*, for the reception of the ordinary stand-pipe may also be provided.

The platform may have further support 40 upon the building through the medium of any suitable braces adapted to be inserted into the wall of the same or otherwise secured thereto; but as I make no claim to any such braces I will not further describe them.

45 The upper faces of cross-bars *b*, hereinbefore referred to, are corrugated, as at *e*, where-

by any ice accumulating thereon is broken and dislodged when pressed upon by the foot of the person using the platform. Cross-bars *b* are strengthened by suitable downwardly-projecting flanges or ribs, *f*, and said bars are curved downwardly from the center toward each side edge, as shown clearly in Fig. 2.

By this construction of the parts the ice when dislodged is free to pass through the 55 openings formed by the bars *b*, and no ice is accumulated, as in the case with platforms as heretofore constructed, wherein the openings have been largest at the top.

The bars of which the platform is composed are T-shaped in cross-section with the cross-piece slightly curved upon each side edge. By this formation of the bars all the 60 advantages requisite to a useful platform are obtained, a wide and comfortable foot-rest 65 is obtained, no snow or ice can lodge upon or between the bars, and strength is secured together with lightness and with the use of little material.

I am aware that platforms composed of bars 70 diamond-shaped in cross-section are not new, and also that bars oval-shaped in cross-section are in use; but in both of such constructions one or more of the advantages of my arrangement cannot be secured. When the diamond-shaped bar is used a sharp edge is presented, which is liable to cut the shoe or foot of the 75 user, and ice or snow frequently lodges between the bars, while in the oval-shaped bar, if a broad surface is to be obtained, bars of considerable weight are necessary.

What I claim is—

A platform for fire-escapes, composed of a series of bars roughened upon their upper faces and T-shaped in cross-section, as set 80 forth.

In testimony whereof I affix my signature in presence of two witnesses.

RICHARD HAMMILL.
